UNITED STATES PATENT OFFICE.

ELMER L. WILLIAMS, OF BUCHANAN, MICHIGAN.

CLOVER-HULLER.

SPECIFICATION forming part of Letters Patent No. 323,475, dated August 4, 1885.

Application filed March 21, 1885. (No model.)

To all whom it may concern:

Be it known that I, ELMER L. WILLIAMS, a citizen of the United States, residing at Buchanan, in the county of Berrien and State 5 of Michigan, have invented certain new and useful Improvements in Clover-Hullers, of which the following is a specification.

The objects of my improvements are to provide a clover-huller which will do the hulling and separating more thoroughly than the hullers now in use, which will save all the seed, and one in which the hulling cylinder and concave can be taken out and repaired without disturbing any other parts of the machine. 10 I obtain these objects by the mechanism illustrated in the accompanying drawings, in which—

Figure 1 is a side view of the machine; Fig. 2, a longitudinal vertical section through the same; Fig. 3, a vertical cross-section on line $x-x$ on Figs. 1 and 2; Fig. 4, a longitudinal vertical section through the hulling cylinder and concave; Fig. 5, a vertical cross-section through the hulling cylinder and concave, 25 showing also part of the cylinder and of the concave in elevation; Fig. 6, a detail view of the lugs or projecting rubber sections, which, bolted in place in continuous rows, form the inside of the hulling-concave; Fig. 7, a detail view of the teeth on the periphery of the hulling-cylinder; Fig. 8, a large scale longitudinal vertical section through the hulling-cylinder and adjoining parts; Fig. 9, a large scale vertical cross-section through the hull- 30 ing-cylinder and adjoining parts; Fig. 10, a large scale longitudinal vertical section through the tailing-box and the end of the cleaning-shoe, with the removable stem-cut-off bar.

Similar letters refer to similar parts throughout the several views.

The sides of the rubber sections h are shown corrugated on only a few of the studs in Figs. 2 and 4, so as not to obscure the drawings. For the same reason not all the cylinder-sections are section-lined on Fig. 3.

A is the frame-work of the machine, mounted on the running-gear S S, and forming the chamber B, in which the thrashing, hulling, and separating are done.

C is the thrashing-cylinder; D, the rakes or

separating device. Said separating device is constructed in the usual manner, with longitudinal bars d^2 d^3 , between which the raker-bars d d , that are provided at the top with the fingers d' d' and at the bottom with the forks d^2 d^3 , operate, the bars d d being connected to a crank-shaft, by which they receive the forward and backward motion. E is a solid bottom extending across the chamber B. The 55 raker-bars d d , being mounted on and operated by a crank-shaft, move the straw over the bars d^2 d^3 toward the rear of the machine, discharging it there, while the seed, chaff, &c., being shaken and separated from the straw by the 60 lifting and shifting movement of the fingers d' d' , drop through between the raker-bars d d and the bars d^2 d^3 onto the floor E, from where they are removed by the forks d^2 d^3 toward the front and to the hulling-cylinder G. 70

F is a screen-slide, which extends across the chamber B, and can be drawn out when desired. O is a shaking floor, oscillated in the usual manner, slanting from under the thrashing concave and cylinder C back to the mouth 75 of the hulling-cylinder G, and conveying any seed separated from the straw by the thrashing-cylinder C and the fore end of the rake D to said hulling-cylinder G.

R is a distributing screw-conveyer. The 80 tailings, &c., that are elevated from the tailing-box j by the elevator L into this conveyer R are by its screw distributed across the width of the machine and emptied into the hulling-cylinder G. By placing the distributing conveyer R back of and close to the hulling-cylinder G, and thus emptying the tailings directly into the hulling-cylinder G, I obtain better results than where the tailings are emptied into the thrashing-cylinder or onto 85 the separating-rakes, in which case the straw becomes more or less clogged and burdened, so that a certain amount of seed will not be separated from the same, but be carried out with it at the rear.

b is a solid bottom under the screw-conveyer R, slanting towards the hulling-cylinder and forming a front continuation of the floor E and the screen-slide F.

The hulling cylinder and concave G are all 90 located below and back of the thrashing-cylinder C, and constructed in the following man-

ner: To the cylinder-shaft g is keyed at one end the cylinder-head g' . Then a cylinder-section, g^2 , provided with the teeth $t t t$ on its periphery, is slipped over the shaft g close up to the cylinder-head g' and firmly secured in place on the shaft. Then a cylinder-section, g^3 , with corrugated periphery, is slipped over the shaft g tight up to the section g^2 , and secured to the shaft g ; then another section, g^2 and g^3 , and so on, until the hulling-cylinder is completed by another head-piece g' .

The concave H , which is made in two halves crosswise, is lined on the inside with the arc-shaped projecting rubber sections or lugs $h h$, which are bolted to the concave H by the bolts $h^2 h^2$. The rubber sections $h h$ have corrugated sides and a corrugated surface toward the hulling-cylinder, provided with a hole, h' , for the bolt h^2 to pass through, the sides of the rubber sections slanting out toward the concave H . The rubber sections $h h$, being bolted to the concave H in continuous parallel rows spaced at equal distances apart laterally, form V -shaped grooves, through which the teeth $t t$ of the cylinder-sections g^2 pass. The teeth $t t$, being either firmly secured to or forming part of the sections g^2 , have corrugated sides and top surface and a smooth beveled front edge or lead or forward portion. This smooth beveled lead or forward portion, while taking hold of the chaff, weeds, stems, and seed, gradually flattens the same out in the corrugated grooves without causing any clogging or cracking of the seed, and no seed will be pushed ahead of the teeth out of the concave without being hulled. The teeth are in the shape of an inverted V , being thicker at their base than at the top, corresponding to the grooves formed by the sides of the rubber sections $h h$, in which grooves the teeth $t t$ operate. By having the teeth thicker at their base more strength is given to them, and the liability of their breaking off of the cylinder lessened.

The cylinder-sections $g^3 g^3$ may either have thin corrugated surface-plates secured to their periphery, or the surface of the sections may be cast or worked corrugated.

The corrugated teeth $t t$, operating and fitting closely in the corrugated grooves formed by the rubber sections $h h$, and the corrugated surface of the cylinder-sections $g^3 g^3$ coming close to the corrugated surface of the concave rubber sections $h h$, a very large rubbing surface and a device is obtained in which the hulling is done most effectively, so that none or only very few seeds will leave the concave unhulled. The concave being constructed in the described manner can easily be repaired. There being no large sections of lining, but only the small rubber sections $h h$, damaged or broken studs can be taken out and replaced with little trouble and expense. The cylinder, being formed in sections slipped over and secured to the shaft g , can also easily be repaired, broken sections can be replaced,

and, another great advantage, the cylinder can perfectly be balanced.

The entire hulling concave and cylinder are secured to a frame, P , which frame rests upon cross-beams of the frame A , and is secured in position by bolts and nuts or other suitable means, and can be drawn out of the chamber B laterally when the concave or cylinder needs repairs. When in place the frame P is secured to the machine-frame A by butts or any other suitable devices. By having the hulling concave and cylinder thus made removable I am enabled to make repairs to them without disturbing any other parts of the machine, which insures a great saving of time and labor.

The removable screen-slide R' is located right back of the distributing screw-conveyer R . Its office is to allow the seed which has already been hulled by having undergone the thrashing and shaking process to drop onto the cleaning shoe and riddle I without passing through the hulling-cylinder G , thus lessening the work of the cylinder and preventing any clogging and cracking of the seed. It also enables me to use the machine for thrashing timothy, the seeds dropping through said screen F onto the riddle I . When the screen F should become clogged with dirt, chaff, or seed it can be drawn out and cleaned.

I is the cleaning-shoe, oscillated in the usual manner, i being the riddle, i' the sieve, and i^2 the screen, slanting forward to the seed-chute N .

k are the pitman-rods and lever, which, being connected with an eccentric on the fan-shaft K , or any other shaft, oscillate the shoe I .

The improvement I make in the cleaning-shoe I is as follows: I extend the screen-floor i^2 of the shoe I beyond the ends of the riddle and sieve i and i' , and there secure to said floor a removable cut-off bar, p , extending over and across the entire floor i^2 . If this bar p is placed back of the ends of the riddle and sieve i and i' , the stems or heavier substances that are not entirely blown out of the chamber B by the blast of the fan K drop from the ends of the said riddle and sieve i and i' onto the screen-floor i^2 , are prevented from going over the end of said screen-floor i^2 into the tailing-box j by the aforesaid cut-off bar p , and slide down on the screen i' , emptying into the stem-chute M . If it is desired to have the stems and heavier substances undergo the hulling and cleaning process a second time, on account of the seed that may yet be contained in the same, I change the location of the cut-off bar p so that it is under the ends of the riddle and screen i and i' , as shown by dotted lines on Figs. 2 and 10. The stems will then drop into the tailings-box j , will be elevated from there by the common-elevator, L , and be emptied into the distributing-conveyer R , which, extending across the chamber B , conveys the same to the hulling-cylinder G . The

cut-off bar p is secured in either position to the screen-floor i^2 by nails, screws, clamps, or other suitable means which will admit of changing the location of the bar without much trouble or loss of time.

5 N is the chute into which the clean seed collect that have passed through the cleaning-shoe I onto the floor J. The stem-chute M is constructed in the following manner: A 10 solid slanting bottom, m' , extends across the entire width of the machine, while a little above the same is located a perforated false bottom, m , running out some distance over one end at the bottom m' . The stems slide 15 down on the perforated floor m , and drop onto the ground, while any seed that may be left with the stems drop through the false bottom m onto the floor m' and empty into a box or measure attached to the end of the floor 20 m' . By having the stem-chute M constructed thus I save whatever seed may pass with the stems beyond the seed-chute N.

By locating the hulling concave and cylinder back of the thrashing-cylinder, and arranging the different parts of the machine as 25 described and shown on the drawings, I obtain an arch back of the front wheels, which allows said front wheels to turn without interfering with the frame-work of the huller.

30 My machine, constructed as described, can be used for hulling either clover or rice, and for thrashing timothy.

Having thus fully described my improvements, what I claim, and desire to secure by 35 Letters Patent, is—

1. In a hulling-cylinder, the combination of a shaft, g , cylinder-heads $g' g'$, disk-sections $g^2 g^2$, provided with corrugated projecting teeth $t t$, constructed as described, and disk-sections $g^3 g^3$, alternating with the sections $g^2 g^2$ and being provided with corrugations on their outer surface, the sections $g^2 g^2$ and $g^3 g^3$ being firmly secured to the shaft g , so as to balance 40 and form the cylinder G, substantially as described.

2. A hulling-cylinder comprising the shaft g , the cylinder-heads $g' g'$, the toothed sections $g^2 g^2$, and the corrugated sections $g^3 g^3$, said sections keyed upon the shaft g , substantially 45 as described and specified.

3. In combination with a hulling-cylinder, the teeth $t t$, each secured to the cylinder-sections $g^2 g^2$, and having corrugated outward tapering sides, a corrugated outer face, and a

beveled lead or forward portion with smooth 55 sides, substantially as shown and described.

4. A grooved hulling concave composed of a suitable supporting-bed and arc-shaped rubber sections, each formed with a corrugated face and corrugated sides and secured in place 60 by bolts, as described and specified.

5. In a hulling cylinder and concave, the combination, with the cylinder-shaft g , the cylinder-heads $g' g'$, the cylinder-sections $g^2 g^2$, provided with the projecting corrugated teeth 65 $t t t$, with smooth beveled front portions, and the cylinder-sections $g^3 g^3$, having their peripheries corrugated, of the concave-frame H, and the arc-shaped projecting sections $h h h$, secured to said frame H, and having corrugated sides 70 and faces forming grooves for the teeth $t t t$ of the cylinder-sections $g^2 g^2$ to operate in, all substantially arranged as described, and for the purpose specified.

6. In a clover-huller, the combination, with 75 the frame-work A, the chamber B, the thrashing-cylinder C, the rakes and separating device D, the solid stationary floor E, and the laterally-removable screen-slide F, located in said floor E back of the hulling-cylinder G 80 and over the cleaning-shoe I, of the hulling concave and cylinder H G, located back of the thrashing-cylinder C, as described, the shaking inclined floor O, extending from under the thrashing-cylinder C to the mouth of 85 the hulling-concave H, the cleaning-shoe I, and the fan K, all arranged as described, and for the purpose specified.

7. In a clover-huller, an oscillating cleaning-shoe I, comprising the riddle i , the sieve i' , placed beneath the riddle i , the screen-floor i^2 , situated under both the riddle and sieve and extending out beyond the ends of the same in front and rear, and the adjustable stem-cut-off bar p , secured to the rear of and 90 across the screen-floor i^2 , where desired, in combination with the frame-work A of the machine, the slanting bottom J, the tailings-box 95 j , and the fan K, substantially as described, and for the purpose specified. 100

In testimony whereof I have signed my name to this specification in the presence of two subscribing witnesses.

ELMER L. WILLIAMS.
